US00D324375S

United States Patent [19]
Kato et al.

[11] **Patent Number:** **Des. 324,375**
[45] **Date of Patent:** **** Mar. 3, 1992**

[54] **CONTROL UNIT FOR AN ELECTRONIC COMPUTER**

[75] **Inventors:** **Yoshiharu Kato; Chitose Ono**, both of Tokyo, Japan

[73] **Assignee:** **NEC Corporation**, Tokyo, Japan

[**] **Term:** **14 Years**

[21] **Appl. No.:** **521,466**

[22] **Filed:** **May 9, 1990**

[30] **Foreign Application Priority Data**

Nov. 10, 1989 [JP] Japan 1-41138

[52] **U.S. Cl.** **D14/100; D14/102; D14/109**

[57] **CLAIM**

The ornamental design for a control unit for an electronic computer, as shown.

DESCRIPTION

FIG. 1 is a front elevational view of a control unit for an electronic computer showing our new design;
FIG. 2 is a right side elevational view thereof;
FIG. 3 is a top plan view thereof;
FIG. 4 is a left side elevational view thereof;
FIG. 5 is a rear elevational view thereof;
FIG. 6 is a bottom plan view thereof; and
FIG. 7 is a front, top and right side perspective view thereof.

FIG. 1

FIG. 2

FIG. 3

FIG. 4

FIG. 5

FIG. 6

FIG. 7
